UNITED STATES PATENT OFFICE.

FERDINAND MAX EUGEN BLASS, OF MÜLHEIM-ON-THE-RHINE, GERMANY, ASSIGNOR,
BY MESNE ASSIGNMENTS, TO THE CHEMICAL FOUNDATION, INC., A CORPORATION
OF DELAWARE.

GAS PRODUCER.

1,414,109.

Specification of Letters Patent. Patented Apr. 25, 1922.

Application filed November 24, 1915. Serial No. 63,232.

To all whom it may concern:

Be it known that I, FERDINAND MAX EUGEN BLASS, a citizen of the German Empire, and resident of Mülheim-on-the-Rhine, Germany, 5 have invented certain new and useful Improvements in Gas Producers, of which the following is a specification.

My present invention relates to gas producers and has for its object to provide a gas 10 producer of great efficiency, of simple and durable construction, which will overcome the numerous defects generally found in gas producers of the character employed hitherto.

15 The features and advantages of my invention will be fully described hereinafter, and its novel characteristics pointed out in the appended claims.

Four typical examples of my invention are 20 shown in the accompanying drawings, in which Fig. 1 is a central vertical section through the producer, and Fig. 2 is a horizontal section taken on line 2—2 of Fig. 1; Fig. 3 is a central vertical section of a modification; Fig. 4 is a central vertical section through the lower portion of a third form of construction; Fig. 5 is a central vertical section through a fourth form of construction, and Fig. 6 is a section on line 6—6 of Fig. 5.

30 In each of the constructions shown, the body 10 of the producer is made of fire brick or other suitable material and contains a chamber 11, 11' or 11'' to which fuel is supplied through the filling opening or the inverted funnel 12, normally closed by a cover 13' or 13. At its bottom, this upper chamber communicates with a lower chamber 14, also adapted to contain fuel, and the two chambers meet at about the level of the lower 35 edge of an inner wall or partition 15, 15', or 15'' which separates the upper chamber 11 from an adjacent gas chamber 16, 16', or 16'' from which the gas produced is conveyed to the place of storage or use. The lower portion of the chamber 14 is contracted after the 40 fashion of a funnel, and at the bottom there is located a pan 17, 17', or 17'' adapted to contain water and also to receive the ashes from the gasified fuel. The pan is normally 45 closed at the outer end (as will be described presently), and preferably there is an overflow pipe 18, 18', or 18'' for keeping the water in the pan from rising beyond the desired level. However, I desire it to be understood that I do not restrict myself to the 50 details shown, and that the novel features of

my invention, as they are defined in the appended claims, may be applied to gas producers of types other than those illustrated in the drawings; more particularly, the upper portion of the producer may be modified in various ways.

In the construction illustrated by Figs. 1 and 2, the gas chamber 16 surrounds the upper fuel chamber 11 and communicates with the lower fuel chamber 14 through openings 19 at the lower edge of the partition 15, while a pipe 20 serves to conduct the gas away from the chamber 16 to the place of storage or consumption. Immediately below the contracted portion of the chamber 14, I provide a hollow wall or tank 21, surrounding a space which is in axial alignment with the lower end of the fuel chamber 14. This tank 21 communicates with one or more 55 smaller tanks 22 serving as steam collectors and preferably located at a slightly higher level. These tanks 22 are separated from the fuel chamber by the brickwork of the producer, that is to say, the incandescent fuel is 60 not in direct contact with the walls of the tanks 22. The communication between the tanks may be effected, for instance, by means of hollow brackets 23. Water is supplied to one of the communicating tanks (say, the 65 lower tank 21) in any suitable manner, as by a pipe 24, the supply being controlled by the manual adjustment of a valve (not shown), or automatically, as by the well-known float control (not shown). Each of the upper 70 tanks 22 is provided in its outer wall with a steam outlet 22' arranged adjacent to, and preferably at a slightly lower level than, a corresponding air outlet 25' located at the 75 inner wall of an air chamber 25, which receives air in any suitable manner; in the drawing, I have indicated an air inlet 25'' regulated by a valve 26, but if desired, compressed air (heated or not) may be supplied to said chamber through a suitable pipe (not shown). The air heated in the chambers 25 and the steam generated in the chambers 21, 22 pass out through the openings 25' and 22' respectively and become intimately mixed as they pass downwardly in the spaces between the tanks 22 and chambers 25 to a mixing chamber 27 located above the pan 17 and communicating with the combustion chamber. The pan 17, or rather the mixing chamber or chambers 27, are closed at the outside 80 by suitable doors 28, say hinged doors connected with counterbalancing weights 29 and

normally dipping into the water contained in the pan 17.

The operation of this form of my invention is as follows: Fuel charged into the producer through the top comes to rest on a temporary support formed by kindling wood or the like disposed in the lower part of the chamber 14 or in the contraction or throat surrounded by the annular tank 21. The tanks 21, 22 and the pan 17 are filled with water and kept full (to the desired level) during the entire operation. Fire having been started and the chambers 11, 14 having been filled with fuel, and the operation having assumed its regular course, the heat of combustion will reach the material in the upper chamber or fuel reservoir 11, causing the fuel therein to be freed of volatile constituents. Since the cover 13 is closed, the gas will be forced by its expansion etc. through the incandescent fuel to the gas outlet 19, 16, 20, and during this operation, the light oils, tar, etc. produced in the chamber 11, are gasified. The production of gas takes place both in the chamber 11, where certain constituents (tar, etc.) are removed from the fuel and gasified, and in the chamber 14, where the fuel itself is gasified. The lower portion of the chamber 14 is not only exposed to a much more intense heat than the chamber 11 and the upper part of said chamber 14, but is traversed in an upward direction, from the bottom opening to the gas outlet, by a current of air mixed with steam well distributed over the entire area of the fuel. This mixture, as it passes through the incandescent fuel layers, causes first (in the lower portion) a formation of CO_2 and then (in the layers above) a gradually increasing reduction to CO , so that the final gaseous product contains a minimum of CO_2 . The air is preheated to a certain extent in the chamber 25 and on its further way to the chamber 14, and if a greater degree of preheating is desired, this may be attained by any of the well-known means. The steam generated in the tanks 22 and 21 and forcibly admixed to the air in the chamber or chambers 27, will greatly assist in producing a rich gas of high heating value, and will also have the useful effect of granulating the slag and ashes produced in the lower part of the chamber 14. The entire operation proceeds uniformly, the gas obtained is of constant good quality, and the height of the effective reduction layer or of the fuel charge for the gasifying or reduction zone is also constant. The cooling action of the water in the tank 21 will protect the wall of said tank which is exposed to a high temperature, against premature wear, and I utilize for the production of steam, the heat absorbed by said wall, which heat otherwise would be wasted. The slag slides down along the central cone 10' into the pan 17,

from which it can be removed readily, the doors 28 being swung open for this purpose. The generation of steam adjusts itself automatically to the degree of heat. The pan 17 receives its supply of water from the overflow of the tanks 22.

The modification illustrated by Fig. 3 differs from the construction described with reference to Figs. 1 and 2, by the construction of the ash pan and the parts connected therewith. The pan 17' is annular, with its inner wall flush with the central cone 30 (preferably rotary in this case), and into this pan dips the lower edge of a stationary conical wall 31. The pan itself is supported on bearing balls 32 and is rotated about the center of the producer (axis of cone 30) by a suitable driving mechanism 33. The overflow is discharged from a pipe 18' into a stationary annular gutter 34. In other respects, this construction will be the same as the one illustrated by Figs. 1 and 2, and the operation will be the same. As the ash pan 17' rotates, the ashes and slag will be removed automatically in any suitable way, as by a stationary scraper or ejector 35. The conversion of any fuel into gas is so complete that tar pockets or tar collectors are not required in connection with the gas mains. Of course, if desired, the by-products may be recovered from the gas in apparatus of any well-known or approved character.

In the modification illustrated by Fig. 4, the lower portion of the producer is similar to the one shown in Fig. 1, except that there is only one opening, normally closed by a door 28', for giving access to the ash pan 17''. The upper fuel chamber or fuel reservoir 11' is inclined downwardly and rearwardly, and the partition 15' is likewise inclined instead of vertical as in Figs. 1 and 2. The inclined fuel chamber is widened toward the bottom, to facilitate the downward movement of the fuel. The producer shown in Fig. 4 is intended particularly for making gas from soft coal (with natural draft), while the producer shown in Figs. 5 and 6 is intended to use coke or other loose fuel. The tank 21' forms a steam generator and collector provided with a steam outlet 21'', the steam being deflected downward by a baffle 35, and then becoming mixed with the (heated) air issuing from a conduit 25*.

The upper part of the producer shown in Figs. 5 and 6 is of the same general character as in Fig. 4, but the chamber 11'' and the gas flue 16'' (separated from said chamber by a partition 15'') are substantially vertical. The tank 21', however, is omitted, and the lower portion of the inclined front wall of the lower fuel chamber 14 is formed by a step grate of peculiar novel construction. This grate comprises cheek-plates 36 supporting grate bars 37 arranged in stag-

gered fashion, that is to say, each grate bar projects inwardly or rearwardly beyond the grate bar immediately above it. Each of these grate bars is trough-shaped, being provided with a relatively low front wall 37', and with a relatively high rear wall 37'', the latter being adjacent to the chamber 14. On the underside of its bottom, each grate bar 37 is provided with a rib 37* extending 10 transversely, that is to say, ranging from one cheek plate 36 toward the other, said ribs being located directly above the troughs of the grate bars immediately below them. As shown in Fig. 6, the lower edge of each 15 rib 37* is preferably inclined downwardly from the points adjacent to the cheek plates 36 to the center, so that the water will not flow down the cheek plates, but will follow the ribs 37* and drip into the next trough 20 below. The inside surface of the bottom wall of the grate bar is inclined toward the center, where a notch 37 in the front wall 37' and a vertical rib 37^b are provided to better guide the overflowing water. Other 25 suitable constructions of these grate bars may be employed. At the bottom of the chamber 14, there is a second grate 38, preferably inclined from front to rear as shown, and supported on a front carrier 39 and on 30 a rear carrier 40. Between the lowermost grate bar 37 and this lower grate 38, I leave a space sufficient for the passage of a suitable tool (to be introduced through the open door 28*) for pushing the ashes on the 35 grate toward the rear and dump them into the pan 17'' through the opening or clearance 41 provided at the rear of the grate. The grate bars 37 come very close to each other, that is to say, only a narrow space 40 is left between the bottom of a grate bar 37 and the upper edge of the rear wall 37'' of the next grate bar below. The air coming from openings in the door 28* controlled 45 regulatably by a valve 42, passes partly below the grate 38 and up through the same, and partly through the narrow spaces between the grate bars 37, and over the water contained in said grate bars and in the pan 17'', which water is being converted into 50 steam. The air is forcibly mixed with the steam produced in the apparatus. The spaces between the grate bars are preferably of such width and shape as to prevent any fuel or ashes from dropping into the trough-shaped grate bars. The ribs 37*, 37^b form 55 barriers to stop and guide the flow of water so that the water will pass from one trough-shaped grate bar to another and finally to the pan 17''. It will be seen that the trough-shaped grate bars 37 offer a very large surface for conducting the heat from the burning fuel to the water, so that a large part 60 of the water contained in, and flowing over, the said grate bars will be converted into 65 steam, which steam will greatly assist in

producing a gas of high value and well-granulated slag. In this form of my invention also, the air may be preheated, if desired, in any well-known or approved manner. Water is supplied to the uppermost 70 grate bar 37 through a pipe 43, having a regulating cock or valve 43'.

Various modifications may be made without departing from the nature of my invention as set forth in the appended claims. 75

I claim:

1. A gas producer provided with a fuel inlet and means for normally closing it, a downwardly-widening chamber connected with said inlet and adapted to serve for the 80 storage, preheating, and subsequent distilling of fuel, a gasifying chamber forming the downward continuation of the first-named chamber, a gas outlet channel rising from said gasifying chamber adjacent to the first-named chamber so as to heat the latter, a downwardly-tapering combustion chamber immediately below said gasifying chamber and communicating therewith, a steam generator located laterally of said combustion 85 chamber and provided with outlets, a water pan located below said combustion chamber to receive ashes therefrom, and means for directing a current of air into the combustion chamber past the outlets of said steam 90 generator, and over the surface of the water contained in said pan.

2. A gas producer provided with a downwardly-contracted fuel-containing chamber, an annular steam generator located below 100 the contracted portion of said chamber and having a cylindrical inner wall, and means for carrying the steam from said generator into the said chamber.

3. A gas producer comprising a fuel chamber having a gas outlet and a contracted bottom, a water tank surrounding said contracted bottom and forming a steam generator, a steam collector connected with said tank but out of contact with the fuel, said collector 105 having an outlet for the escape of steam and the overflow of surplus water, means for supplying water to said tank, a pan located under said chamber and adapted to receive the ashes from the burning fuel and the 110 overflow from the steam generator, and means for supplying air to the burning fuel.

4. A gas producer comprising a fuel chamber having a gas outlet and a contracted bottom, a water tank surrounding said contracted bottom, a steam collector connected with said tank and provided with an outlet 115 for the escape of steam and the overflow of surplus water, an air chamber arranged adjacent to the said collector and having an air outlet adjacent to said steam outlet, and a pan located below the bottom of the fuel chamber and below the outlet or overflow of the steam collector.

5. A gas producer having a water-pan at 120

the bottom, a steam generator located above said pan, and a fuel-chamber extending downwardly adjacent to said generator beyond the upper level of said generator, said 5 chamber widening upwardly from the upper end of said steam generator.

6. A gas producer having a water-pan at the bottom, a steam generator located above said pan and provided with outlets, 10 a fuel-containing chamber extending downwardly to substantially the same level as the bottom of said steam generator, and means for directing a current of air into said chamber past the outlets of the steam generator 15 and over the surface of the water contained in said pan.

7. A gas producer having a steam generator and a fuel chamber extending downwardly adjacent to said generator beyond the 20 upper level of said generator, said chamber widening upwardly from the upper end of said steam generator.

8. A gas producer provided with a fuel inlet and means for normally closing it, a 25 downwardly-widening chamber connected with said inlet and adapted to serve for the

storage, preheating, and subsequent distilling of fuel, a gasifying chamber forming the downward continuation of the first-named chamber, a gas outlet channel rising 30 from said gasifying chamber adjacent to the first-named chamber so as to heat the latter, a downwardly-tapering combustion chamber immediately below said gasifying chamber and communicating therewith, a steam generator located laterally of said combustion chamber and provided with outlets, and means for directing a current of air into the combustion chamber past the outlets of said steam generator. 40

9. A gas producer provided with a fuel-containing chamber having a centrally-located fuel inlet at its upper portion, and an annular gas-collector chamber surrounding said fuel inlet, and a perforated wall forming an annular series of restricted openings 45 through which said annular chamber communicates with the portion of the fuel-chamber thereunder.

In testimony whereof I have signed this 50 specification.

FERDINAND MAX EUGEN BLASS.
